UNITED STATES PATENT OFFICE.

LOUIS V. ARONSON, OF NEWARK, NEW JERSEY.

IGNITER.

Application filed March 30, 1922. Serial No. 548,051.

To all whom it may concern:

Be it known that I, LOUIS V. ARONSON, a citizen of the United States, residing at Newark, in the county of Essex and State 5 of New Jersey, have invented certain new and useful Improvements in Igniters, of which the following is a specification.

The invention relates to gas igniters, and has as an object the provision of an igniter 10 for lighting gas burners which will have a long life for use, which will be convenient to use, and which will give a brilliant shower of sparks for the purpose.

An illustrative embodiment of the invention is shown in the accompanying drawings, in which—

Figure 1 is a side elevation;

Figure 2 is a plan view and

Figure 3 is an exploded detail perspective view of portions of the device.

As shown in Fig. 1, the device comprises a frame 10 constructed of a single piece of material, being bent into a downwardly directed loop 11 to provide a handle, an upper horizontal portion 12 to which the trigger 13 is pivoted, a portion 14 downwardly offset from the portion 12 and extending horizontally forward, and extremity 15 of the material being doubled backward 25 upon the portion 14 and turned downwardly at an angle thereto.

The second end of the material 16 is turned upwardly at an angle to a lower horizontal portion 17 and the vertical portions 15 and 16 are perforated by means 35 of slots 18—19.

A reciprocating member 20 is adapted to slide through the slots 18 and 19 and, as shown, carries a friction member 21, shown 40 as a piece of file secured at its forward end as by being seated in a recess 22 and by having portions of the material of the member 20 upset over it as at 23—24. To return the member 20 to the position shown in 45 Fig. 1 a coil spring 25 is shown surrounding the member 20 seating against the portion 16 of the frame as an abutment and acting upon the member 20 by seating against a pin 26 passed therethrough.

To retract the member 20 the trigger 13 having an end 27 passing through a slot 28

in the frame acting as a fulcrum and also working through a slot 29 in the member 17 of the frame, has a pin 30 coacting with a notch 31 in the member 20.

As the trigger 13 is moved to the rear by the finger of the user the pin 30 will travel in the arc of a circle and the member 20 will be moved to the rear until its extremity 32 abuts against the portion 33 of the frame when its rearward motion will be checked. At this time the pin 30 will be on the portion of its arc which is curving upwardly and continued motion of the trigger will release the pin from the notch 31, allowing the member 20 to be snapped to its normal position.

A cylinder 34 is shown as mounted in the forward end of the portion 14 of the frame, and a piece of pyrophoric material 35 is seated in the cylinder and pressed against the file 21. To provide pressure upon the pyrophoric material a spring 36 is shown mounted upon a loop 37 secured to the portion 14 of the frame, the loop 37 passing 75 through the coils 38 of the spring. An end of the spring is seated in a perforation 39 in the frame and the other end 40 seats in slots 41 in the cylinder 34 and presses upon the end of the pyrophoric material 35. 80

The friction element 21 by its sudden forward movement in contact with the pyrophoric material will produce a brilliant shower of sparks sufficient to readily ignite a gas burner.

To return the trigger 13 to normal position after ignition of the member 20 a coil spring 42 is shown anchored upon an extension of the pin 30 and in an opening 43 at the base of the portion 16 of the frame. 90 The member 20 being pressed downwardly by spring 36 at its forward end will have a fulcrum in the lower end of the slot 19, causing the portion bearing the notch 31 to be resiliently pressed upwardly. When the trigger 13 is returned the member 20 will be pressed downward by the pin 30 with yielding of spring 36 until its position over the notch is reached when the notch will be pressed upward into engagement with 95 the pin 30 in readiness for a subsequent operation. Since the trigger 13 is centrally

housed in the frame and since the slots 18-19 are also centrally placed in the frame, the member 20 is provided with a lateral offset at 44, so as to bring the portion of the member 20 opposite the trigger to one side of the trigger.

Minor changes may be made in the physical embodiment of the invention without departing from its spirit.

10 I claim:

1. An igniter comprising, in combination, a frame comprising a pair of spaced vertical portions having slots therein, a reciprocating member acting in said slots, a spring 15 abutting against one of said portions and against an element of said reciprocating member to return said member to normal, a trigger pivoted in said frame having an element coacting with a notch in said member, said member adapted to contact with a portion of the frame at the rearward limit of its motion whereby the trigger is released from the member with sudden return of the member to normal position, a friction element moved by said member, a pyrophoric element in contact with said friction element.

2. An igniter comprising a frame formed of a strip of material bent to form a handle loop, a horizontal portion and a pair of spaced portions extending perpendicular to said horizontal portion, said last named portion having slots, a reciprocating member mounted in said slots and extending 35 into the handle loop, a spring anchored to one of said spaced portions to return said member to normal, a friction element actuated by said member, a pyrophoric element carried by said horizontal portion in contact with said friction element, means mount-

ed in the frame to actuate said reciprocating member.

3. An igniter comprising a frame, a notched reciprocable member mounted in the frame, a portion of the frame adapted 45 to limit the movement of the member from its normal position and to deflect the member laterally at the end of its movement from normal, a trigger having an element coacting with the notch in said member and 50 adapted to release said member when its limit of movement from normal is reached, a spring to return said member to normal, a friction element actuated by said member and a pyrophoric element in contact with 55 said friction element.

4. An igniter comprising a strip of material bent on itself to form a loop, a portion of the loop bent downwardly to form a handle and a portion thereof extending forwardly and having slots in its members, a portion of said strip extending forwardly from said loop, the end of said forwardly extending portion doubled on itself and the extremity bent downwardly and slotted, the 60 other extremity of the strip bent upwardly 65 toward the forwardly extending portion and slotted, a notched reciprocable member working in said last named slots, a trigger fulcrumed in one of said first named slots 70 and guided in the other thereof, a stud on said trigger coacting with said notch to retract the reciprocable member and release the same, a spring to return the reciprocable member to normal position, a friction element actuated by said reciprocable member 75 and a pyrophoric element in contact with said friction element.

LOUIS V. ARONSON.
